UNITED STATES PATENT OFFICE.

GUSTAF JOHNSON, OF PIGEONCOVE, MASSACHUSETTS.

VOTING-MACHINE.

SPECIFICATION forming part of Letters Patent No. 737,412, dated August 25, 1903.

Application filed February 5, 1903. Serial No. 142,002. (No model.)

To all whom it may concern:

Be it known that I, GUSTAF JOHNSON, a citizen of the United States, and a resident of Pigeoncove, in the county of Essex and State of Massachusetts, have invented a new and Improved Voting-Machine, of which the following is a full, clear, and exact description.

The object of the invention is to provide a new and improved voting-machine arranged to permit a voter to vote by manipulating certain mechanical devices or by resorting to writing, to allow voting a straight ticket or for candidates individually, to allow separate voting by females, and voting for amendments, licenses, &c.

The invention consists of novel features and parts and combinations of the same, as will be more fully described hereinafter and then pointed out in the claims.

A practical embodiment of the invention is represented in the accompanying drawings, forming a part of this specification, in which similar characters of reference indicate corresponding parts in all the views.

Figure 1 is a perspective view of the improvement. Fig. 2 is an enlarged rear sectional elevation of the same, part of the casing being removed and part being shown in section. Fig. 3 is a sectional plan view of part of the same on the line 3-3 of Fig. 2. Fig. 4 is a transverse section of the improvement. Fig. 5 is an enlarged sectional rear elevation of one of the detail mechanisms of the voting device for each set of candidates.

Fig. 6 is a transverse section of the same. Fig. 7 is an enlarged rear sectional elevation of the same, showing parts in a different position. Fig. 8 is a sectional plan view of the same. Fig. 9 is a face view of one of the levers. Fig. 10 is an enlarged rear elevation of one of the resetting devices. Fig. 11 is a sectional plan view of the same on the line 11-11 of Fig. 10. Fig. 12 is an enlarged rear sectional elevation of the ingress and egress controlling device for the voter. Fig. 13 is a like view of the same, showing parts in a different position. Fig. 14 is a sectional plan view of the same on the line 14-14 of Fig. 12.

Fig. 15 is a like view of the same on the line 15-15 of Fig. 14. Fig. 16 is a similar view of the same on the line 16-16 of Fig. 13; and Fig. 17 is an enlarged sectional front elevation of

the devices for holding, by resorting to writing, the names of the candidates.

The improved voting-machine is mounted on a suitably-constructed casing A, arranged in a booth or like structure, and the entrance to the front of the machine is guarded by an entrance-lever B, arranged at one end of the casing, and an exit-lever C, located at the other end of the casing, the voter standing in front of the casing between the said levers when voting. The entrance-lever B is normally in a lowermost position, and when the voter desires to vote he raises the lever B and then steps in front of the casing, the lever B then immediately swinging back and automatically locking itself in this position to prevent the voter from passing out at this end of the machine and to prevent other persons from passing to the voter while he is voting. Swinging the lever B upward, as described, causes unlocking of the exit-lever C, so that the voter after voting can swing the lever C upward, whereby the entrance-lever B is unlocked to allow a second voter to enter the booth to vote. Thus the entrance-lever B is unlocked on the voter swinging the exit-lever C upward, and the latter is unlocked on the voter swinging the lever B upward.

For the purpose described the following device is provided, special reference being had to Figs. 2, 12, 13, 14, 15, and 16. The entrance-lever B has its pivot B' arranged in the form of a shaft journaled in suitable bearings in the casing A, and on the said shaft, inside the casing, is secured a gear-wheel B², in mesh with a gear-wheel D', secured on a shaft D, extending longitudinally in the casing and journaled in suitable bearings on brackets E E', attached to the inside of the casing. On the shaft D is secured a cam-wheel D², having a beveled face adapted to engage a correspondingly-shaped face on the hub F' of an arm F², secured to a rod F, mounted to slide longitudinally in the brackets E E', and the said rod F is provided with a second arm F³, adapted to engage the beveled head F⁵ of a hook-link F⁴, extending through a slot in the side of the casing to pivotally connect at its outer end with the heel C' of the exit-lever C, fulcrumed at C² on the outside of the casing. On the shaft D, adjacent to the arm F², is secured a locking-wheel

D^3 , having on its peripheral face a flat portion D^4 , (see Fig. 16,) adapted to be engaged by a locking-hook F^6 , fulcrumed on the rod F and pressed on by a spring F^7 , the said locking-hook F^6 being adapted to lock the wheel D^3 against turning at the time the entrance-lever B is in a lowermost position and the voter stands in front of the casing. (See Fig. 12.) Now when the voter is through voting he swings the exit-lever C upward, and in doing so the heel C' pulls on the hook-link F^4 to draw the arm F^3 , shaft F , arm F^2 , and locking-hook F^6 toward the exit-lever into the position shown in Fig. 13, whereby the locking-hook F^6 is moved longitudinally out of engagement with the flat portion D^4 of the cam-wheel D^3 , and hence the shaft D is unlocked. At the same time that this takes place the beveled face of the hub F' moves into contact with the beveled face of the cam-wheel D^2 . The voter when leaving the booth swings the exit-lever C downward, whereby the head F^5 of the hook-link F^4 moves out of engagement with the arm F^3 , and consequently the latter and the parts connected therewith—that is, the rod F , arm F^2 , and locking-hook F^6 —remain stationary in the position shown in Fig. 13. Now when the next voter swings the entrance-lever B upward then the gear-wheels $B^2 D'$ are turned, causing the shaft D to rotate, so that the cam-wheel D^2 by its beveled face acting on the beveled face of the hub F' moves the latter, and with it the arm F^2 , rod F , locking-hook F^6 , and arm F^3 , toward the entrance-lever B to the position shown in Fig. 12, and as soon as the lever B swings downward then the locking-hook F^6 is forced by its spring F^7 over onto the flat portion D^4 of the wheel D^3 to lock the shaft D against turning and the entrance-lever B against upward swinging motion until unlocked by the voter swinging the exit-lever C upward, as before explained. When the arm F^3 moves toward the entrance-lever, as previously explained, then it again engages the head F^5 of the link F^4 to connect the arm F^3 with the exit-lever C .

The swinging motion of the levers B and C , as described above, is limited, and for this purpose the lever B moves in a guideway B^3 , the ends of which form stops for the lever, the guideway being preferably formed in a casing B^4 , secured to one end of the casing A . The exit-lever C swings between two pins $C^4 C^5$, secured on a segment C^6 , attached to the other end of the casing A , as plainly shown in Fig. 1.

On the shaft D are secured a plurality of transversely-extending arms D^6 for controlling, locking, unlocking, and setting the voting devices arranged in the casing A and actuated by the voter using a key on a key-spindle G , extending transversely and mounted to turn in suitable bearings arranged in the front of the casing A . The key-spindles G are arranged in vertical rows, as plainly indicated in Fig. 1, and on the casing A at the top of each row is a legend A' , indicat-

ing straight tickets, offices of candidates to be voted for, licenses, schools, &c., the arrangement being such that the voter, for instance, can vote a straight ticket by turning the corresponding key-spindle in the first row, whereby the remaining key-spindles in the whole casing become locked, and hence the voter cannot turn any other key-spindle in the casing. In case the voter does not vote a straight ticket he can turn in each following vertical row as many key-spindles as there are persons to be elected for the corresponding offices—that is, for instance, in the row for governor a single voter can only turn one of the key-spindles G , as only one governor is to be voted for. In case three councilmen, for instance, are to be elected then the voter can turn any three key-spindles, but no more, in the row under the heading "Council." The second-last row, marked "School," is provided with key-spindles G' , having a different key-slot for the use of a different key in the hands of a female voter, so that the female voter can vote under "School," but cannot use the key in any other row.

On each key-spindle G and G' is secured a wheel H within the casing A , and the said wheel H is provided with two diametrically-disposed teeth for meshing with corresponding teeth on a rack I , mounted to slide up and down in the casing, and on the lower end of each rack I is fulcrumed a longitudinally-extending bar J , adapted to be engaged on its top by a corresponding cross-arm D^6 of the shaft D , and the free end of the said bar J rests on the foot-piece K' of a slide K , disposed vertically on the other side of the key-spindles G in one row, as plainly illustrated in Figs. 2, 5, and 7. Now when the cross-arm D^6 of the shaft D rests on the bar J and the shaft D is locked then neither the rack I nor the slide K can be raised. When, however, the shaft D has been turned on, swinging the entrance-lever B upward, then the cross-arm D^6 swings upward and releases the several bars J of all the voting devices to allow the voter to turn a key-spindle G or G' half-way around for the corresponding tooth of the wheel H to lift the rack I .

On each key-spindle G is secured a cam-wheel L , having two diametrically-disposed teeth adapted to be engaged by a dog L' , fulcrumed at L^2 on the casing A and pressed by a spring L^3 to hold the head of the dog in engagement with the peripheral face of the cam-wheel. By the arrangement described the key-spindle G cannot be turned in a reverse way.

On one face of the cam-wheel L or directly on the key-spindle G is secured a cam L^4 for imparting an upward swinging motion to a locking-lever N , fulcrumed at N' on the casing and provided with an abutment-shoulder N^2 for a tooth of a locking-wheel O to abut against after the voter has given a half-turn to the key-spindle, the said locking-wheel O

being secured to the key-spindle G and having two diametrically-disposed teeth for successive engagement with the abutment-shoulder N². (See Fig. 7.) The locking-lever N is adapted to engage with its free end N³ a pin K² on the slide K to lift the latter at the time the rack I is raised.

On the free end N³ of the locking-lever N is fulcrumed at P' an indicating-lever P, having a pin P², engaging an elongated slot P³, formed in the casing A. The free end of the indicating-lever P is provided with contrasting face portions P⁴ P⁵ (see Fig. 9) for appearing successively in the rear of an aperture P⁶, formed in the front of the casing A adjacent to the corresponding key-spindle G. (See Figs. 1 and 6.) The face portion P⁴ is preferably white, and is normally in register with the opening P⁶; but when a half-turn is given to the key-spindle G by the voter using the key then the upward swinging motion given to the locking-lever N causes a swinging of the indicating-lever P to bring the face portion P⁵, which is preferably red, in register with the aperture P⁶ to indicate to the voter that the adjacent key-spindle G has already been turned by him, and hence the voter does not insert the key again in this spindle.

In order to allow of setting the voting device for each row to allow voting for one, two, three, or more candidates, the following device is provided:

On the lower end of each rack I is slidably held a collar I', adapted to be fastened in place on the rack by a set-screw I², and this collar I' is adapted to abut against the under side of a bracket I³, in which the rack I and slide K are free to move. When one candidate in a row is to be voted for, then the collar I' of this particular rack I is set a distance from the brackets I³ so that when the rack I is raised by the voter giving a half-turn to the key-spindle G then the collar I' abuts against the brackets, and consequently the rack I cannot be moved farther up—that is, none of the key-spindles G of this voting device can be turned. When two candidates for one office are to be voted for, the collar I' is set twice the distance from the bracket I³, and consequently the rack I can be twice lifted on turning two key-spindles G in the same row, as then the collar I' is brought against the under side of the bracket I³. As shown in Fig. 2, the collar I' of the first voting device on the left-hand side shows the voting device set for three candidates, while the next voting device is set for two candidates, and the third one is set for one candidate, and the rack is at the end of its uppermost position—that is, the voter has given a half-turn to a key-spindle of this voting device.

It will be understood that when the racks I are in the lowermost or normal position the teeth of the wheels H, secured to the key-spindles, are out of mesh with the teeth of the

racks, and consequently when a key-spindle is turned by means of the key furnished the voter one of the teeth on the wheel H of that spindle only engages the rack and lifts the same.

As before described, in order to prevent the operation of more than one key-spindle in a row when only one candidate in that row is to be voted for the collar I' is previously so adjusted on the rack I with reference to the bracket I³ that when a half-turn is given to one of the key-spindles then the collar I' will abut against the bracket, and consequently none of the other key-spindles in that row can be turned, as the rack is locked by the collar I' against further upward movement.

In order to hold each rack I in a lowermost or raised position, each rack is provided at its lower end with a pivoted catch Q, pressed on by a spring Q' and engaging a notched bar Q². (See Figs. 2 and 10.) Now when the rack I is in a lowermost position the catch Q engages the lowermost tooth, as shown in Fig. 10, and when the rack I is successively raised, as above explained, then the catch Q engages corresponding teeth in the bar Q² to hold the rack I in whatever position it is moved. On the heel end of the catch Q is formed a foot Q³, extending transversely to engage the notched under side J' of the bar J, so that when the rack I is raised the bar J is raised, and when the voter is through voting and the shaft D is turned and the arm D⁶ swung downward then the several arms engage the bar J and swing the same downward to disengage the catches Q from the bars Q² to release the racks I for the same to slide back into a lowermost position. Now it will be seen that the slides K are raised but one distance, no matter how many key-spindles are turned in one row, and consequently the bar J when pressed downward into this lowermost position by the arm D⁶ engages the foot K' and draws the slide back into its lowermost position.

The first rack I for the straight-ticket-voting device is provided with a pin R', engaging the slotted end of a bell-crank lever R, fulcrumed on the casing A and pivotally connected with a locking-slide R², having sets of shoulders R³ R⁴ for engagement by tongues I⁴ and K³, formed on the racks I and slides K, respectively. (See Fig. 3.) Now when the voter turns one of the key-spindles in the straight-ticket-voting device then the upward movement of the rack I imparts a swinging motion to the bell-crank lever R, so that the slide R² is shifted longitudinally to bring the notches R³ and R⁴ in register with the corresponding tongues I⁴ and K³ to lock all the remaining racks I and slides K of the other voting devices to prevent the voter from turning any of the other key-spindles.

When the machine is reset by the turning of the shaft D, as above explained, then the downward movement of the rack I for the

straight-ticket-voting device imparts a return swinging motion to the bell-crank lever R to move the locking-slide R² out of a locking position relative to the tongues I⁴ and K³.

5 In order to prevent the racks I from being propelled too far on turning a key-spindle, a brake device is provided, consisting of a brake-block I⁵, hung on a pivot I⁶, supported from the casing, and the free end of the said brake-block is pressed on by a spring I⁷ to hold the brake-block in frictional engagement with the rack. (See Figs. 2 and 4.) Each of the key-spindles G and G' is connected with a registering device S, of any approved construction and arranged to register one vote for each half-turn given by a voter with a key to the corresponding key-spindle G or G'.

The lowermost key-spindles G³ of each vertical row of spindles except the first one, 20 which is a blank, control voting devices different from the preceding ones and designed to enable the voter to write the names of the candidates for each office, and as these devices are alike in construction it suffices to 25 describe but one in detail.

Each key-spindle G³ carries at its inner end a bevel gear-wheel T (see Figs. 2 and 4) in mesh with a pinion T', secured on the upper end of a vertically-disposed shaft T², 30 journaled in suitable bearings arranged within the casing A. On the lower end of this shaft T² is secured a pinion T³ in mesh with a gear-wheel T⁴, secured on a transversely-extending shaft T⁵, journaled in suitable bearings 35 and projecting to the front of the casing A into an auxiliary casing A⁴, arranged on the front of the casing A. On the shaft T⁵ within the auxiliary casing A⁴ is secured a roller U, operating in conjunction with a second roller 40 U' for drawing a strip of paper V between the said rollers U and U' and over a table W, formed in the casing A⁴ directly under the opening A⁵, arranged in the top A⁵ of the said casing A⁴. The strip of paper V un- 45 winds from a roll V' and winds up on a roll V², driven from the roller U by a pulley U², secured on the roller U and connected by a belt U³ with a pulley U⁴ on the roll V². Now when a voter inserts a key in the key-spindle 50 G³ and turns the same then the gearing described causes rotation of the shaft T⁵ and roller U, as well as the roll V², to wind up the paper on the roll V² to cause the paper to travel in the direction of the arrow a' over 55 the table W. The voter, by the use of a pencil or other writing implement, can now write on the strip of paper presented under the opening A⁵ on top of the table W the name of the candidate he desires to vote for, 60 independent of the remaining voting devices. The roller U' is journaled in a frame U⁵, pressed on by a spring U⁶, so as to hold the roller U' with the desired pressure in contact with the strip of paper passing over the roller 65 U. A spring tension device V³ is arranged on the roll V', as plainly indicated in Fig. 4, to prevent the roll V' from unwinding the

strip of paper too fast at the time the roll V² is rotated from the roller U, as above described. The auxiliary casing A⁴ is provided with a 70 door A⁶, locked by keys in the possession of the authorities, to enable the latter to obtain access to the rolls after the voting is done.

From the foregoing it will be seen that the voter can vote a straight ticket of any party, 75 and in this case it is only necessary for him to give one-half turn to the corresponding key-spindle G in the first row, and in voting in this manner the remaining voting devices are all locked. In case the voter votes for individual candidates he can vote in each row only for as many candidates as the device is set for by the adjustment of the collars I', as previously explained. The key-spindles G' 80 in the second last row can only be actuated by keys of a different construction than the ones used by the male voters, and consequently the vote of the females is separately registered.

Having thus described my invention, I 90 claim as new and desire to secure by Letters Patent—

1. A voting-machine having a plurality of manually-controlled key-spindles, located one above the other, a rack having teeth, a toothed 95 wheel on each key-spindle, having two diametrically-disposed teeth for engaging the rack, a locking-wheel on the key-spindle having two diametrically-disposed teeth, a locking-lever provided with an abutment-shoulder 100 for engaging a tooth of the locking-wheel, to hold the latter from turning, and a cam-wheel turning with the locking-wheel and engaging the lever, to throw the latter out of engagement with the tooth of the locking-wheel, to 105 allow turning of the key-spindle, as set forth.

2. A voting-machine having a plurality of manually-controlled key-spindles, located one above the other, a rack having teeth, a toothed wheel on each key-spindle, for engaging the 110 rack, a locking-wheel on the key-spindle having two diametrically-disposed teeth, a locking-lever provided with an abutment-shoulder for engaging a tooth of the locking-wheel, to hold the latter from turning, a cam-wheel 115 turning with the locking-wheel and having teeth adapted to be engaged by a dog, a cam turning with the cam-wheel and engaging the lever, to throw the latter out of engagement with the tooth of the locking-wheel, to allow 120 turning of the key-spindle, and a setting device for the said rack, to limit the sliding motion thereof, as set forth.

3. A voting-machine having a plurality of manually-controlled key-spindles, located one 125 above the other, a rack having teeth, a toothed wheel on each key-spindle, for engaging the rack, a locking-wheel on the key-spindle, a locking-lever having an abutment-shoulder for engaging a tooth of the locking-wheel, to hold the latter from turning, a cam-wheel turning with the locking-wheel and engaging the lever, to throw the shoulder of the latter 130 out of engagement with the tooth of the lock-

- ing-wheel, to allow turning of the key-spindle, and a setting device for the said rack, to limit the sliding motion thereof, comprising a collar held adjustable on the rack and a fixed abutment for the collar to abut against when the rack is raised the prescribed distance, as set forth.
4. A voting-machine having a plurality of voting devices of which one is for voting a straight ticket, the said voting devices each being provided with a rack and a slide, and means for locking the remaining voting devices on actuating the straight-ticket-voting device, the said means comprising a bell-crank lever connected with the rack of the straight-ticket-voting device, and a slide connected with the bell-crank lever and having sets of shoulders adapted to be engaged by tongues on the racks and slides of the remaining voting devices, as set forth.
5. A voting-machine provided with a plurality of voting devices, of which one is for voting a straight ticket, and means for locking the remaining voting devices from the said straight-ticket-voting device, consisting of a notched slide, a bell-crank lever connected with the notched slide and controlled by the straight-ticket-voting device and engaging tongues on the other voting devices, as set forth.
6. A voting-machine having a manually-controlled key-spindle, a toothed wheel thereon, a rack for engagement by the toothed wheel, a cam-wheel on the spindle, a locking-lever controlled by the cam-wheel, a locking-wheel on the spindle, adapted to be locked by the said locking-lever, a fixed toothed bar, and a spring-pressed catch on the rack, engaging the toothed bar, as set forth.
7. A voting-machine having a manually-controlled key-spindle, a toothed wheel thereon, a rack for engagement by the toothed wheel, a cam-wheel on the spindle, a locking-lever controlled by the cam-wheel, a locking-wheel on the spindle, adapted to be locked by the said locking-lever, a fixed toothed bar, a spring-pressed catch on the rack, engaging the toothed bar, a slide engaged by the said locking-lever, and a bar fulcrumed on the rack and engaging a foot-piece on the said slide, as set forth.
8. A voting-machine having a manually-controlled key-spindle, a toothed wheel thereon, a rack for engagement by the toothed wheel, a cam-wheel on the spindle, a locking-lever controlled by the cam-wheel, a locking-wheel on the spindle, adapted to be locked by the said locking-lever, a fixed toothed bar, a spring-pressed catch on the rack, engaging the toothed bar, a slide engaged by the said locking-lever, a bar fulcrumed on the rack and engaging a foot-piece on the said slide, and an arm on the catch, engaging the said pivoted bar, as set forth.
9. A voting-machine provided with a voting device having a manually-controlled rack and a slide, a bar fulcrumed on the rack and engaging a foot-piece on the said slide, a shaft, an arm thereon, for engaging the said bar, and manually-controlled means for turning the said shaft, as set forth.
10. A voting-machine provided with a rack, a key-spindle, mechanism on the key-spindle for actuating the rack, and a brake device for the said rack, as set forth.
11. A voting-machine provided with a rack, a key-spindle, mechanism on the key-spindle for actuating the rack, and a brake device for the said rack comprising a pivoted brake-block, and a spring engaging the free end of said brake-block to hold the same in frictional engagement with the rack, as set forth.
12. A voting-machine having a casing, a plurality of key-spindles journaled in the front of the casing, voting devices controlled by the key-spindles, and indicating-levers each having a pin engaging a slot in the casing, the said levers being controlled by the voting devices and having contrasting faces adapted to appear successively in an opening in the front of the casing adjacent to the key-spindles, as set forth.
13. A voting-machine having a casing, a key-spindle journaled in the front of the casing, a voting device actuated from the said key-spindle, a locking-lever fulcrumed on the casing, and forming part of the voting device, and an indicating device comprising a lever fulcrumed on the free end of the locking-lever, and having a pin engaging a slot in the casing, the said lever being provided at its free end with contrasting faces adapted to appear successively in an opening in the front of the casing adjacent to the key-spindle, as set forth.
14. A voting-machine, comprising a plurality of manually-controlled key-spindles located one above the other, and a voting device for each row of key-spindles, including a rack and a slide actuated from the spindles, as set forth.
15. A voting-machine comprising a plurality of manually-controlled key-spindles located one above the other, and a voting device for each row of key-spindles, including a rack actuated from the key-spindles, and a pivoted and spring-pressed catch for holding the rack in a lowermost or raised position, as set forth.
16. A voting-machine having a plurality of manually-controlled key-spindles, located one above the other, a rack actuated from the key-spindles, means for holding the rack in a lowermost or raised position, and an adjustable collar on the lower end of said rack and adapted to engage the under side of a bracket in which the rack is free to move, to limit the sliding movement of the rack, as set forth.
17. A voting-machine provided with a voting device having a manually-controlled rack and a slide, a bar fulcrumed on the rack and

engaging the slide, and means for holding the said bar and adapted to be moved to release the same, as set forth.

18. A voting-machine, comprising a plurality of manually-controlled key-spindles located one above the other, a voting device for each row of key-spindles and each including a rack and a slide, bars fulcrumed on the racks and engaging the corresponding slides, a shaft mounted to turn, a plurality of arms thereon for engaging the said bars, and manually-controlled means for turning the said shaft, as set forth.

19. A voting-machine, comprising a plurality of manually-controlled key-spindles located one above the other, a voting device for each row of key-spindles and having a rack and a slide, bars fulcrumed on the racks and engaging the corresponding slides, and means for engaging and holding said bars and adapted to be moved to release the same, as set forth.

20. A voting-machine provided with a voting device having a manually-controlled rack

and a slide, a bar fulcrumed on the rack and 25 engaging a foot-piece on the said slide, a spring-pressed catch pivoted on the rack and engaging a fixed tooth-bar to hold the rack in a lowermost or raised position, and a projection on the said catch engaging the under 30 side of said bar, as set forth.

21. A voting-machine having a key-spindle, a toothed wheel thereon, a rack for engagement by the toothed wheel, a cam-wheel on the spindle, a locking-lever controlled by 35 the cam-wheel, an indicating device controlled by the locking-lever, a slide engaged by the locking-lever, a bar fulcrumed on the rack and engaging the said slide, and means for holding the rack in a lowermost or raised position, as set forth.

In testimony whereof I have signed my name to this specification in the presence of two subscribing witnesses.

GUSTAF JOHNSON.
